Primary Examiner — Cynthia R Underwood(74) *Attorney, Agent, or Firm* — Kelly & Kelley, LLP(57) **CLAIM**

The ornamental design for a hinge, as shown.

DESCRIPTION

FIG. 1 is a perspective view of a hinge embodying my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side view thereof; and,

FIG. 7 is a left side view thereof.

The dotted circular lines show typical areas where apertures are provided for mounting the hinge. The broken lines represent portions of the structure that forms no part of the claim.
